UNITED STATES PATENT OFFICE

ALFRED ALSAKER, OF CHICAGO, ILLINOIS, ASSIGNOR TO THE DELTA-STAR ELECTRIC COMPANY, OF CHICAGO, ILLINOIS, A CORPORATION OF ILLINOIS

ROTARY INSULATOR

Application filed September 27, 1926. Serial No. 137,926.

My invention, in general, relates to electrical mechanism, and more particularly to rotary insulators such as those employed in conjunction with the operating of the blades 5 of switches and the like. More specifically the present invention pertains to rotary switches.

While I shall describe the invention as embodied in an outdoor disconnect switch in 10 which the switch blade is mounted on a rotatable insulator, I do not wish to limit the invention to this particular embodiment nor to this particular switch.

A disconnect switch normally is opened 15 only when a piece of apparatus or a line is taken out of service. Hence, it may stand in closed position for relatively long periods of time.

In recent times there has been a rapid increase in transmission voltages and as a result thereof the insulation and striking distance dimensions have been compelled to keep pace therewith. Obviously, the greater the length of the insulator and the blade, the 25 greater is the necessity for accuracy in the fit of the moving parts. This is particularly true of the bearing for the rotary insulator in a rotary switch, since any play or looseness in such bearing would result in failure of the 30 blade to keep its alignment with the switch contacts.

Another element to be taken into consideration in connection with outdoor switches is sleet, i. e., ice frozen upon the switch. It is 35 evident that the larger the switch blade, the greater is the resistance offered to opening of the blade when covered with sleet. Similarly, the resistance to closing is increased by the length of the blade.

In order to provide a switch operable in 40 all kinds of weather and at any time without fail, various forms of the so-called "opening movement" have been devised. I have illustrated the present invention in a switch 45 having one form of the so-called "A. R. T." movement of my invention. Such movements generally provide a change of direction of movement of the switch blade by a mechanism capable of exerting great force 50 upon the blade to break it loose from the con-

tact when it is held by sleet or corrosion, or merely the friction of the grip of the stationary contact.

In rotary switches employing the above type of movement, the rotary insulator is put 55 under considerable stress. The bearing will, in operation, tend to become loosened. Attempts have heretofore been made to obviate the above difficulty by the use of a relatively large close fitting bearing. This bearing, 60 however, does not solve the problem because corrosion and sleet will freeze such a bearing so tight that it cannot be operated or moved.

A plain cylindrical bearing which has a 65 sufficiently tight fit to give the desired guiding action to a long blade or the like, of necessity prevents such an extensive capillary area between the cylindrical surfaces of the moving part and its stationary bearing part, that if moisture or corrosion become 70 lodged in the same the two parts will be so firmly frozen together that the switch cannot be opened. This, of course, is fatal to switch operation.

I have solved the difficulty by the provision of a ball bearing support for the insulator. A mechanic would not think of putting a fine piece of mechanism like a high grade ball bearing out in the exposed condition without operation or attention for long 75 periods of time, as is the case in an outdoor disconnect switch. I wish to call attention to the fact that I employ the ball bearing not so much in its capacity to stand high speeds and continuous operation with low friction 80 as I do to provide a relatively accurately aligned bearing which cannot be frozen or corroded fast. If the bearing does corrode or fill with sleet, the balls will cut their way through the same. This is because the bearing is substantially free of any capillary recesses in which moisture could be drawn in and frozen or in which corrosion could lock the parts together. The balls which are employed in the bearing have substantially only 85 point contact with their cooperating surfaces, and furthermore they present a leverage to break away any film of moisture or corrosion which may freeze the parts together. This employment of ball bearings to 90

eliminate freezing due either to ice or corrosion, is fundamentally new in the art.

In the manufacture of my bearing, I do not harden and grind the races for the balls as the service which is required of the bearing is of such a character that such fine finish would be not only wasted, but would be a detriment. I purposely leave the races soft and depend upon the balls to finish or fit the surface. Also if any corrosion or freezing does occur, the balls can cut their way through it and, in extreme cases, stretch or strain the metal of the races without cracking the same.

In my novel bearing, I attempt to keep out the moisture and corrosive matter as much as possible by providing an eave or watershed over the bearing and by keeping the bearing at all times full of grease.

In accordance with the preferred form of the present invention, there is provided a rotary insulator comprising an insulator proper to which suitable blade mechanism is affixed, a revolvable supporting element removably attached to the insulator unit, a fixed support concentric with the revolvable support, a plurality of ball-like elements intermediate the two supports, and means for tightly holding the two supports in a contiguous position, the said support, in reality constituting a ball bearing unit so to speak. Also, manual means is associated with an end of the revolvable support by means of which the same may be actuated. Then, too, I form the portion of the revolvable support adjacent the insulator in such a manner that an actuating handle or crank may be readily attached thereto if it is desired to actuate the insulator from a position above the fixed support or transmit motion from it.

Other objects and advantages of the present invention will more fully appear from the following detailed description taken in connection with the accompanying drawings which illustrate one embodiment thereof and in which

Fig. 1 is a plan view of a rotary type switch embodying the features of my invention;

Fig. 2 is an elevation of my novel type of rotary insulator in section;

Fig. 3 is a fragmentary sectional view taken on the line 3—3 of Fig. 2 illustrating the manner in which the manual actuating member is associated with the insulator;

Fig. 4 is a horizontal sectional view taken through the mounting of the switch blades of the rotary switch illustrated in Fig. 1;

Fig. 5 is a sectional view taken on the line 5—5 of Fig. 4 looking in the direction indicated by the arrows;

Fig. 6 is a sectional view taken on the line 6—6 of Fig. 4 looking in the direction indicated by the arrows; and

Fig. 7 is a sectional view taken on the line 7—7 of Fig. 5 looking upwardly.

Referring now to the drawings in details in which like reference numerals designate similar parts throughout the several views, reference characters 1 and 2 designate a pair of spaced insulators of any usual construction mounted upon a fixed channel beam support 27. The support 27 is of a U-like shape, as best shown in Fig. 2 and is grounded in any suitable or desirable manner. Positioned on the support intermediate the spaced insulators 1 and 2 is a rotary insulator indicated generally by the reference numeral 10. Associated with the insulator 10 is a switch blade unit 11, the mounting of which will be more fully described hereinafter. The ends of the switch blade unit 11 are adapted to cooperate with contacts or terminals 3 and 4 carried by the insulators 1 and 2, respectively. Carried by the terminal 3 or connected thereto is a lug 7, by means of which an electrical conductor is connected to the terminal. Similarly associated with the terminal 4 is a lug 8 for enabling the connection of an electrical conductor with the terminal 4. The terminal 3 carries an arcing horn 5 adapted to cooperate with an arcing horn 6 carried by one end of the switch blade unit 11. Likewise, the terminal 4 carries an arcing horn 9 adapted to cooperate with an arcing horn 9' carried by the other end of the switch blade unit 11. The switch blade unit 11 is adapted to cooperate with the terminals or contacts 3 and 4 in a manner well known to those skilled with the switch art.

I shall now proceed to describe in detail my novel mounting for the rotary insulator 10. As best illustrated in Fig. 2, 10 denotes generally an insulator unit which may be made of any suitable or usual insulating material, such, for example, as porcelain having a stem or post and a cap secured thereto as by cementing. The lower end of the stem of insulator unit 10 has a flat surface 12 adapted to contact the top of a hollow cast metal supporting element or spindle member 13. The spindle member 13 is preferably a hollow casting of malleable iron or bronze at the junction of the head and spindle an annular radial shoulder 14 which constitutes one part of a ball bearing unit hereinafter to be described. Extending through the bore 15 of the tubular element 13 is the shank 16 of a bolt 17, the head of which abuts the lower end of the element proper. The shank 16 is provided with a plurality of threads 17', one end which is adapted to be threaded into a threaded aperture 18 in the lower end of the insulator unit 10. The bolt 17 when in place, serves to secure the element 13 to the insulator unit 10.

Formed in the lower end of the insulator unit 10 are a plurality of apertures 20, and formed in the top of the element 13 are a

plurality of apertures 21 in line with the apertures 20. Fitted in each pair of apertures 20 and 21 is a pin 22 to key or pin the parts together. The pin 22 serves to properly align the face 12 of the lower end of the insulator unit 10 with the top of the supporting element 13.

Surrounding the element 13 and substantially concentric therewith is a malleable or bronze barrel 25 with a conical bearing face 35 forming a ball race which is positioned immediately below the annular shoulder 14 of the element 13. This element 25 is equipped with a laterally projecting flange 26 adapted to rest on the top of the fixed support 27 which is provided with a substantially central aperture 28 through which the body of the supporting element 25 extends. The annular flange 26 may be fastened to the top of the fixed support 27 by any suitable means, such, for example, as bolts and nuts 30.

Separating the inner wall of the element 25 from the outer wall of a reduced portion 31 of the element 13, is an annular space 32 which may be packed with grease, oil or other suitable lubricating medium. Threaded into the wall of the element 25 and connected to the space 32 is a grease cup 33, by means of which the lubricating medium may be introduced into the annular space 32. The upper end of the element 25 is provided with a flared annular portion 35 which constitutes a race for the upper ball bearing unit now to be described. The ball bearing unit comprises a plurality of steel balls 36 positioned intermediate the annular portion 35 and the annular shoulder 14. The shoulder 14 and the portion 35 comprises the two races of the ball bearing unit. The ball bearing unit communicates with the annular grease pocket 32 through an annular clearance 37, through which grease is supplied to the upper ball bearing unit. Both of the races of this ball bearing unit are preferably machined, but present a relatively rough surface to the steel balls 37. I purposely leave the races soft and depend upon the balls to finish or fit the surface. Also if any corrosion or freezing does occur, the balls can cut their way through it and in extreme cases, strain or stretch the metal of the races without cracking the same.

I have found by leaving the races soft, that the balls 36 will tend to form a seat or groove in the races when the insulator is revolved so that a smooth running bearing is formed.

I prevent moisture and foreign matter from getting in the bearing by forming an annular flange or eave 35' integral with the shoulder 14 where the head 13 joins spindle 15.

The lower end of the element 25 is counterbored at 40 to provide a like annular eave embracing the top of a special bronze nut 41 threaded onto the element 13 at 42. The coun-

tersunk portion of the lower end of the element 25 is equipped with an annular flared shoulder 44, between which and the top of the bolt 42 are a plurality of steel balls 45. This shoulder 44 and the top of the nut 41 comprise the races of the lower ball bearing unit. Communicating with this unit is an annular clearance 45', through which grease is fed from the annular space 32. Immediately below the special nut 41 I provide a sheet metal lock washer 50, and threaded on the element immediately below the lock washer is a lock nut 51. The sheet metal washer has ears about its periphery which may be bent to engage the faces of the nut 41 and lock nut 51.

The extreme lower end of the element 13 has formed thereon an annular shoulder 60. The portion of the element 13 between the shoulder 60 and the threads 42 is preferably formed octagonal in shape, as indicated at 61 in Fig. 2. Surrounding this octagonal portion 61 is an end of an operating lever 62 equipped with an octagonal aperture for receiving the said octagonal portion 61. The operating lever is disposed intermediate the shoulder 60 and the lowermost nut 51. This lever 62 comprises a handle portion 63 and a clamp portion 64, removably attached thereto by bolts and nuts 65.

The movement of the lever 62 by a rod as will be hereafter described limits the motion of the spindle and its insulator to an angular motion less than a complete rotation. In the present switch the motion of the lever arm 62 is not substantially more than 90 degrees. This may be varied for different types of switches, but in directly driven switch arms is invariably not more than half a complete rotation.

It should also be noted that the tubular element 13 has a portion 37' thereof formed in such a manner as to be able to have a lever or handle 62 clamped thereto in a way similar to that by which the handle is clamped to the portion 61. That is to say, the portion 37', which is located above the water shed 35' and the support 27 is preferably octagonal in cross section. I have illustrated a handle in dotted lines in connection with the octagonal gripping portion 37'. Thus it will be apparent that the insulator may be actuated from either above or under the fixed support 27.

Now I shall proceed to described in detail my novel mounting for the switch blade unit 11. The blade unit 11 (Fig. 5) is equipped with a central enlarged portion 70 which in reality constitutes a housing for the mechanism associated with and connecting the blade unit 11 to the top of the insulator 10. The central member 70 is substantially hollow, as indicated at 71 in Fig. 5, and is equipped with a pair of diametrically opposite shoulders 72 and 73. The central por-

tion 70 is preferably cast integral with the switch blade unit 11. Positioned within the central member 70 is a curved member 74 (Fig. 4) having a curved slot 75 extending therethrough. The element 74 is secured to the shoulders 72 and 73 by bolts and nuts designated generally by the reference numeral 75'. Mounted upon the element 74 is a movable part 78. This part 78 is pivotally attached to the member or element 74 (Fig. 4) by a pivot pin 79.

The part 78 as best shown in Fig. 7, has an arcuate-shaped portion 80 which extends through the slot 75 in the element 74. Also, as best shown in Fig. 5, the top of the part 78 is equipped with an annular depression 81 which is adapted to accommodate the head of a bolt 82. The bolt 82 extends clear through the member or part 78 and is adapted to fasten the part 78 to the top 85 of the insulator 10. The lower portion of the part 78 or the arcuate portion 80, has secured thereto a pair of dowel pins 86 and 87 which also extend into the top 85 of the insulator 10 (Fig. 5). These dowel pins 86 and 87 serve to prevent movement between the part 78 and the insulator 10. That is to say, the parts 78 and the insulator 10 must turn together in the operation of my novel rotary switch.

The top of the part 78 is equipped with a pair of spaced lugs extending upwardly therefrom. I have indicated these lugs by the reference numerals 90 and 91. Also, the top 35 of the parts 78 is equipped with an upwardly extending projection 92 associated with the pivot pin 79. The top of the part 78 is equipped with a cut-away portion 93 forming shoulders 94 and 95 adapted to cooperate with a pin 96 secured to the member 74. The shoulders 95 and 94 serve to limit the movement of the movable parts 78 about its pivot 40 79. Positioned on top of the part 78 is a spring or resilient element 98, one end of 45 which is adapted to co-operate with one of the lugs 90 or 91 and the other end of which being adapted to cooperate with the pin 96. The portion 99 of the spring intermediate its ends is adapted to abut a flat portion 100 50 on the projection 92, which projection serves to limit the outward displacement of the spring when it is compressed.

The operation of the mechanism associated with the member 70 of the switch blade units 55 11 is briefly as follows:—Upon a rotary motion being imparted to the insulator 10 in a manner well known to those familiar with the rotary switch art, force will be applied to the switch blade units 11 through the part 60 78 which is integral with the top of the insulator 10. The part 78 in turn transmits a force through the spring or resilient element 98 and the pin 96 to the member 74, which member being secured to the switch 65 blade unit 11 will cause force to be applied

thereto. Should the free ends of the switch blade units 11 be relatively loose within their contact terminals 3 and 4, the switch blade units 11 will naturally revolve with the insulator unit 10, as the said insulator unit is actuated. On the other hand, should the free ends of the switch blade unit 11 be frozen to their respectively contact terminals 3 and 4 carried by the insulators 1 and 2, the initial force applied to the switch blade units 11 70 will not result in the immediate rotation of the unit. 75

Referring now to Fig. 4, it will be noted that a portion of the part 78 is adapted to reciprocate within the slot 75 as was previously mentioned. As long as the grip between the switch terminals and the ends of the switch blade unit 11 is greater than the force necessary to compress the spring 98, the initial turning force applied to the part 78 will result in the movement of the part in the slot 75 and the compression of the spring 98. Upon the force being stored up in the compressed spring 98 being strong enough to sever the connection between the ends of the switch blade unit 11 and the terminal, the spring 98 will expand, moving forwardly with it the pin 96 which is integral with the part 74. Since the part 74 is carried by the switch blade unit 11, the entire unit will move outwardly in a longitudinal direction. In other words, the lug 91 will serve to draw one end of the spring 98 toward the end of the spring associated with the pin 96. When the energy in the spring is great enough to sever the connection between the ends of the switch blade unit and the terminals, the pin on the part 74 will be forced forwardly by the end of the spring associated therewith until it comes into contact with the shoulder 94. During the aforesaid longitudinal movement of the part 74, the portion of the part 78 extending in the slot 75 will return to its former position. Thereafter, the force applied to the switch blade unit 11 by the rotary insulator 10 will cause the rotation of the switch blade unit. 100

The previously described movement of first moving the switch blade longitudinally and then causing it to rotate, is what I term an A. R. T. movement. This movement is an ideal one for freeing the ends of the switch blade from the terminals associated therewith should a frozen or corrosive condition exist at the terminals. I desire it understood that I have invented and designed an improved type of rotary switch wherein the entire turning force may be initially employed to move the switch arm longitudinally or in the direction of its length should its ends be frozen in engagement with the contact terminals. That is to say, before the blade is moved angularly, I provide means whereby it may be moved longitudinally to break any frozen condition that may exist. This is 105 110 115 120 125

highly advantageous since, should the blade be frozen in place in the terminal, the effective point of the turning force applied thereto will be at the actual point of application rather than through the leverage arm of the blade between the terminal and the place the force is applied. Thus it will be seen that a comparatively greater effective force will be applied to move the blade endwise out of engagement with the terminal than is the case when the blade is being moved angularly and, hence, any frozen condition is very easily severed.

I shall now proceed to describe in detail the operation and function of my novel bearing for the rotary insulator. It will be evident that should the mounting or bearing for the rotary insulator of my novel rotary switch become frozen, the very advantage of moving the blade longitudinally to break the ice or rust, will be frustrated, since it would in that even preclude the operation of the switch at all.

Therefore, I have invented and designed a novel non-freezing bearing or mounting for the insulator particularly adapted for use in conjunction with my novel switch whereby any frozen condition that may exist at the mounting or bearing of the insulator may be very easily broken and overcome. Incidentally, my non-freezing mounting for the rotary insulator 10 is of anti-friction construction, thereby enabling the insulator to be turned with much less effort than has been possible heretofore.

In order to operate or revolve the rotary insulator 10, the lever 62 must first be attached to the octagonal portion 61 of the supporting or bearing element 13. Three switches of this type for the three phases of a transmission line are generally gang operated. The control insulators 10 are preferably connected together by a cross-bar connected pivotally to arms such as shown in dotted lines in Fig. 2. Then by operating mechanism such as a vertical rotary pipe or a horizontal rod connected to lever 62, the gang may be operated together. I contemplate the provision of operating means either above or below the channel support 27 for revolving the insulators 10. Since both levers are constructed and function in the same manner, it is believed that a description of one suffices for both.

Now, inasmuch as the lever 62 is integral with the element 13, and hence the insulator 10, by moving the lever 62 angularly, the unit 10 may be revolved actuating the switch blade mechanism 11. Although the steel balls 36 and 45 do offer some resistance to the free movement of the element 13, nevertheless, it is much easier to turn the insulator 10 after a long period of time has elapsed since its last operation than has been heretofore possible. The steel balls 36 and 45 tend to

bite into their unfinished, or rather, comparatively soft races when the element 13 is revolved. Also, the lubricating medium in the annular space 32 tends to at all times fill the bearings with a suitable amount of lubrication, thus facilitating their operation.

Now, whenever the races of the bearing unit become worn, the nuts 41 and 51 may be turned a slight amount, thus moving the element 13 bodily down and bringing the balls 36 and 45 into tighter engagement with their respective races.

Another decided advantage of my rotary insulator is the facility with which it may be disassembled for repairs or the replacement of parts. By removing the bolt 17, the insulator 10 may be completely separated from the element 13. Then by taking the lever 62 off the octagonal portion 61 and removing the bolts 41 and 51, the balls 36 and 45 may be removed and the two bearing elements 13 and 25 may be separated. The bearing element 25 is readily detachable from the fixed support 27 by removing the bolts and nuts 30.

Another advantage of my invention is the novel way in which the lubricating medium is fed to the respective ball bearing units. This insures a nicety of action on the part of the ball bearings as well as a relatively smooth movement of the element 13.

Also, the annular space 32 may be filled with grease through the grease cup 33 by the means of any suitable grease gun. The grease in the space 32 will work its way into both the ball bearing units thus affording adequate lubrication therefor and making it much easier to revolve the insulator unit 10.

From the foregoing description it is believed to be evident that it is practically impossible for the parts of my mechanism to become frozen or rusted, so to speak. Then, too, not only is my rotary insulator very easy to operate, but it is of such a simple, compact and inexpensive construction as to make its use in electrical work very practical.

I desire it understood that although I have disclosed and described a preferred form of my invention, that the invention is not to be limited thereby, but only in so far as defined by the scope and spirit of the appended claims.

I claim:

1. A non-freezing bearing adapted to stand exposed to the weather comprising a hollow spindle having an enlarged integral head portion at one end, an integral ball race adjacent the junction of said head and spindle, an overhanging divergent eave for the ball race, a barrel having an integral cooperating ball race disposed under said eave and balls in said races.

2. A non-freezing bearing for outdoor service comprising a hollow spindle having an enlarged head portion at one end, a ball race adjacent the junction of said head and

spindle, an overhanging eave for the ball race, a barrel having a cooperating ball race disposed under said eave, balls in said races, said head having a polygonal formation to provide an attachment for a split clamp, and a flange above said polygonal portion to prevent displacement of the split clamp.

3. A bearing for outdoor service comprising a hollow spindle having an enlarged integral head for mounting an insulator and having an integral ball race formed adjacent the junction of the head and spindle, an eave integral with the enlarged head overhanging the ball race, a barrel member embracing the spindle, said barrel member having a laterally extending mounting flange for supporting the same and having an integral ball race at its upper end disposed under the eave, and balls in said races.

4. In a bearing for outdoor service, the combination of a tubular barrel member having conical races at its upper and its lower ends, an eave overhanging the race at the lower end, a hollow spindle disposed within the barrel member and having radial and circular surfaces forming cooperating ball races for supporting the axial and radial loads on the spindle, balls in said races, an enlarged head for the upper end of the spindle, an overhanging eave extending out over the upper end of the barrel member, a flange at the upper end of the head, and a polygonal portion formed on the head between the flange and the eave to provide a support for a split clamp.

5. In combination, an integral barrel member having a conical race at its upper and its lower end, said barrel member having an eave overhanging the lower race, a hollow spindle embraced by the barrel member, said spindle having radial and circumferential bearing surfaces providing races cooperating with the races of the barrel member, balls in said races, said spindle having an enlarged head portion, an integral eave extending from the head portion over the upper ball race, and non-circular seats on the head member and on the spindle member below the lower ball race for the attachment of split clamp members in predetermined angular positions.

6. In combination, a barrel member having a supporting transverse flange, integral conical ball races at the upper and lower ends of the barrel member, a hollow spindle projecting through the barrel member and having a head at its upper end provided with a non-circular seat for a split clamp, ball races on the spindle cooperating with the ball races on the barrel member, and balls in said races, said spindle having at its lower end a seat for a split clamping member, the seats on the upper and lower ends of the spindle having shoulders for preventing axial displacement of the split clamping members, said seats

permitting the clamping members to be applied in predetermined angular positions.

7. In combination, a barrel member having a supporting transverse flange, integral conical ball races at the upper and lower ends of the barrel member, a hollow spindle projecting through the barrel member and having a head at its upper end provided with a polygonal seat for a split clamp, ball races on the spindle cooperating with the ball races on the barrel member, and balls in said races, said spindle having at its lower end a polygonal seat for a split clamping member, the seats on the upper and lower ends of the spindle having shoulders for preventing axial displacement of the split clamping members, and eaves on the spindle and barrel member for the upper and lower races, respectively.

8. A bearing for a rotary insulator comprising a hollow cast metal spindle having an enlarged head for mounting an insulator and having an integral ball race formed adjacent the juncture of the head and spindle, an eave overhanging the ball race, a cast metal barrel member embracing the spindle, said barrel member having a laterally extending mounting flange and having an integral ball race at its upper end disposed under said eave, said barrel member having a race at its lower end and an eave overhanging said latter race, a bearing nut on the lower end of the spindle, means for locking said nut to the lower end of the spindle and balls in said races.

9. A bearing for a rotary insulator comprising a hollow cast metal spindle having an integral enlarged head portion at its upper end, means passing through the hollow spindle for mounting an insulator post upon said head, shear pins between said head and post, an integral annular race adjacent the junction of the head and spindle, an overhanging eave for the ball race and a barrel member having integral cooperating ball race disposed under said eave and balls in said races.

10. A non-freezing bearing for outdoor switch gear comprising a cast metal mounting barrel having integral ball races, a spindle therein having cooperating ball races, balls in said races, eaves to exclude moisture from the space between said parts, said barrel and spindle having contact only through said balls, said spindle and bearing being substantially free of close fitting cylindrical surfaces which could be frozen or corroded together.

11. A non-freezing bearing comprising a cast metal mounting barrel having integral ball races, a spindle therein having cooperating ball races, balls in said races, eaves to exclude moisture from the space between said parts, said barrel and spindle having contact only through said balls, said spindle and bearing being substantially free of close fitting

cylindrical surfaces which could be frozen or corroded together, and a filling of grease between said barrel and spindle to exclude moisture from the space between them.

12. In combination, a channel bar having an aperture through its web, a cast metal barrel member mounted in said aperture and having an integral clamping flange lying against the web of the channel, a cast metal spindle provided with an integral ball race at each end and having a short divergent flange forming an eave overhanging the upper ball race, said barrel having integral cooperating ball races and having an eave overhanging the lower ball race and balls in said races.

13. In a non-freezing bearing for rotary insulators and the like, a hollow spindle having an integral head provided with a short divergent eave, a ball race formed directly on the spindle under said eave, a barrel having a ball race formed directly thereupon at its upper end, balls between said races, said head having a flat top, a driven member having a flat surface cooperating with said flat top, keys set into said surfaces, and a bolt passing through said hollow spindle and secured to said driven member.

14. A non-freezing bearing comprising a cast metal bearing shell having integral ball races, a cast metal bearing spindle having integral ball races, balls in said races, said races being formed of unhardened metal, and eaves overhanging the space between said shell and spindle.

15. A non-freezing cast metal bearing comprising a bearing shell having integral ball races, a cast metal bearing spindle having integral ball races, said shell and spindle between said races being spaced apart to provide a relatively large recess between them, said races being formed of unhardened metal, hardened balls between said races, and means to exclude moisture from between said shell and spindle.

16. A vertical non-freezing bearing comprising a relatively short open ended hollow shell having integral conical ball races formed thereon at its upper and lower ends, a cast metal spindle having an enlarged head with a flat clamping surface at the top and a divergent eave portion, an integral ball race under said eave portion on the spindle cooperating with the ball race on the upper end of the shell, an adjustable race nut for the lower end of the spindle cooperating with the race at the lower end of the shell, and balls in said races.

17. A vertical non-freezing bearing comprising a hollow shell of cast metal having integral ball races formed thereon at its upper and lower ends, and having an overhanging eave about said lower race, a cast metal spindle having an enlarged head with a flat clamping surface at the top and a divergent

eave portion, an integral ball race on the spindle under said last mentioned eave portion cooperating with the ball race at the upper end of the shell, an adjustable race nut for the lower end of the spindle cooperating with the race at the lower end of the shell, and balls in said races.

18. In combination, a channel bar having a hole through the web thereof, a bearing shell set in said hole and having a clamping flange secured flat against the web of the channel, a spindle in said bearing shell, races on the shell and spindle, balls in said races, said spindle having an enlarged head provided with an overhanging divergent eave portion, said head having at its upper end a flat clamping face, and a rocking arm connected to the spindle for moving the same through a limited angular rocking motion.

19. In combination, a bearing shell, a spindle therein, ball races on the shell and spindle having balls therein, a lever arm having a split clamp with a non-circular inside surface, and the spindle having a non-circular external surface gripped by said split clamp.

20. In combination, a bearing shell having a laterally extending mounting flange and having races at its upper and lower ends, a spindle having an enlarged head at its upper end extending through the shell, said spindle having an overhanging eave at its upper end, ball races on the shell and spindle protected by said overhanging eave, balls in said races, said spindle having a polygonal portion lying outside of the shell, and a rocking lever having a polygonal split clamp for embracing said polygonal portion of the spindle.

21. In combination, a bearing shell having a laterally extending mounting flange, races at the upper and lower ends of the shell, a bearing spindle having cooperating races, an enlarged head at the upper end having an eave overhanging said races, balls in said races, said head having a driven member connected thereto limited to angular motion less than a complete rotation, and a rocking arm connected to the spindle.

22. In a device of the class described adapted to be exposed to the weather and being infrequently operated while in service, a substantially vertical open-ended stationary cylindrical shell having ball races, a rocking spindle member extending through said shell, and having cooperating ball races, balls for said races, a short divergent eave on the spindle above the races shielding the space between races, said shell and spindle being substantially free of close approach to each other except at said ball races to avoid freezing or corroding of said parts together, and means to limit said spindle to a rocking motion of less than a complete revolution.

23. In a device of the class described

adapted to be exposed to the weather and being infrequently operated when in service, a substantially vertical open-ended stationary cylindrical shell having ball races, a 5 rocking spindle member extending through said shell, and having cooperating ball races, balls for said races, a short divergent eave on the spindle above the races shielding the space between races, said shell and spindle 10 being substantially free of close approach to each other except at said ball races to avoid freezing or corroding of said parts together, and a closed grease inlet for filling the space between the shell and spindle with a lubricant which will exclude air and moisture, 15 and means to limit said spindle to a rocking motion of less than a complete revolution.

24. A non-freezing bearing for outdoor switch gear, the combination of a hollow 20 cast metal spindle having an enlarged head with an upper flat end forming an attaching face, an integral annular downwardly divergent flange forming an eave, said spindle having an integral machined peripheral ball 25 race under the eave, said ball race having radial and axial bearing surfaces, said spindle having an integral lower cylindrical ball race, a cast metal bearing shell having a hollow barrel with oppositely inclined conical 30 ball races integral therewith and registering with the ball races on the spindle, a race nut threaded on the lower end of the spindle, a lock nut therefor, one end of the spindle outside the bearings being formed polygonal 35 in shape for the attachment of a split clamp lever in various angular positions, said end of the spindle having an integrally formed flange for preventing endwise escape of a member clamped upon the polygonal portion, 40 the barrel of the shell having an integral radially extending clamping flange for mounting the barrel intermediate its ends.

25. A non-freezing bearing for outdoor service comprising a cast metal spindle, a 45 cast metal shell, said spindle and shell being formed of relatively soft metal and having cooperating integral races, hard metal balls between said races, the spindle and shell being relieved outside of the races to provide clearance, a packing of grease within the shell, and a lever for slowly moving said spindle and shell relative to each other through an annular motion of less than a complete revolution.

55. 26. A non-freezing ball bearing subject to corrosion, having soft metal spindle and barrel members with integral races, hard metal balls of relatively small diameter in said races, a lever connected to the spindle member and operating means connected to the lever and limiting the movement thereof to less than a complete rotation of the spindle.

27. A non-freezing ball bearing subject to periods of inaction and subject to corrosion 60 by exposure to the weather, comprising spin-

dle and bearing members having integral cast metal races, hardened steel balls free of cages and of a small diameter in said races, said balls being adapted to cut through corrosion to the extent of stretching the races, and an 70 operating connection for one of the members capable of imparting less than a complete rotation to the member.

28. A non-freezing bearing subject to corrosion by the weather, comprising cast metal 75 spindle and barrel members having integral machined races with hardened steel balls in the races, and a packing of grease between the members to exclude moisture.

29. A bearing for outdoor switch gear, 80 comprising a hollow cast metal spindle having an enlarged head, said head having a flat end face, a cooperating driven member seated against said flat end face, a bolt passing through the hollow spindle endwise and connecting the spindle and the driven member, said spindle having an integral ball race adjacent the junction of the head and the shank of the spindle and having an integral flange overhanging the race, 85 a barrel member having conical upper and lower races formed directly thereupon, and hardened balls in said races.

30. In combination, a hollow cast metal spindle having an integral enlarged head 90 portion at its upper end, said head being flat on the top, an insulator post flat on the bottom seated directly upon said head, dowel pins between said post and head, a bolt passing through the hollow spindle and secured to the bottom of the post, said spindle having an integral race at the junction of the head and the shank of the spindle, said race having a radial load surface and an axial load surface, a barrel having an integral conical race cooperating with the aforesaid race and balls in said races.

31. In combination, a hollow cast metal spindle having an integral enlarged head 100 portion at its upper end, said head being flat on the top, an insulator post flat on the bottom seated directly upon said head, dowel pins between said post and head, a bolt passing through the hollow spindle and secured to the bottom of the post, said spindle having an integral race at the junction of the head and the shank of the spindle, said race having a radial load surface and an axial load surface, a barrel having an integral conical race cooperating with the aforesaid race, the 105 lower end of the spindle having an integral race with a radial load surface, a ring on the spindle providing an adjustable axial load surface, the lower end of the barrel having an integral conical race cooperating with the race on the lower end of the spindle.

32. In combination, a hollow cast metal spindle having an integral enlarged head 110 portion at its upper end, said head being flat on the top, an insulator post flat on the

bottom seated directly upon said head, dowel pins between said post and head, a bolt passing through the hollow spindle and secured to the bottom of the post, said spindle having an integral race at the junction of the head and the shank of the spindle, said race having a radial load surface and an axial load surface, a barrel having an integral conical race, the barrel having an intermediate clamping flange, the spindle having polygonal clamping portions at each end, and levers provided with polygonal split clamps for attaching them to the spindle above and below the bearing at predetermined angular positions.

33. In outdoor switch gear, a rocking bearing comprising a spindle, a shell of relatively soft metal having yielding metal races, hardened steel balls in said races supporting said spindle, and an operating crank for the spindle limited to angular motion less than a complete rotation, said races being subject to corrosion and the balls being adapted to cut their way through the corrosion even to the extent of causing yielding of the races.

34. In an outdoor gear, a bearing comprising a spindle member, a shell member, said members having integral ball races, one of said races being formed of relatively soft metal, hardened metal balls between said races, said races being subject to corrosion and the balls being adapted to force their way through the corrosion to the extent of causing permanent deformation of the metal of the soft metal race.

In witness whereof, I hereunto subscribe my name this 23rd day of September, 1926.

ALFRED ALSAKER.
